OR D 12,615

No 12,615

Dec. 20, 1881

UNITED STATES PATENT OFFICE.

JAMES W. CAMPBELL, OF PITTSBURG, PENNSYLVANIA.

DESIGN FOR GLASSWARE.

SPECIFICATION forming part of Design No. 12,615, dated December 20, 1881.

Application filed November 7, 1881. Term of patent 3½ years.

To all whom it may concern:

Be it known that I, JAMES W. CAMPBELL, of Pittsburgh, in the county of Allegheny and State of Pennsylvania, have invented a new and useful Improvement in Designs for Glassware; and I do hereby declare the following to be a full, clear, and exact description thereof.

My improved design for glass plates and similar dishes is shown by a plan view in the accompanying drawing, which is a plan view of a bread-plate.

It consists of a vignette representation, in the center, of President James A. Garfield, sur-

rounded by a frosted or ornamental border, *a*, upon which the word "Memorial" is impressed. 15 An ornamental edge gives finish to the dish.

What I claim as my invention is—

The design for glass plates and similar dishes, substantially as shown and described.

In testimony whereof I have hereunto set 20 my hand.

JAMES W. CAMPBELL.

Witnesses:

JNO. K. SMITH,

JAMES H. PORTE.
